UNITED STATES PATENT OFFICE.

EDGAR J. BLOOM, OF TIFFIN, OHIO.

FLUSH-VALVE.

1,323,519.

Specification of Letters Patent.

Patented Dec. 2, 1919.

Application filed September 4, 1917. Serial No. 189,465.

To all whom it may concern:

Be it known that I, EDGAR J. BLOOM, a citizen of the United States, residing at Tiffin, county of Seneca, State of Ohio, have 5 invented a certain new and useful Improvement in Flush-Valves, and declare the following to be a full, clear, and exact description of the same, such as will enable others skilled in the art to which it pertains to 10 make and use the same, reference being had to the accompanying drawings, which form a part of this specification.

This invention relates to flush valves, and has for its object a flush valve which has a 15 novel arrangement for adjusting the length of the flushing operation when the operating handle is held in operative position.

There are also other novel features of 20 structure which will more fully appear in the description following and in the claims.

In the drawings,—

Figure 1 is a vertical section.

Fig. 2 is a vertical section in a 90 degree position from the showing of Fig. 1.

25 Fig. 3 is a view similar to Fig. 1 but fragmentary and showing the valve in open position.

Fig. 4 is a cross section on the line D—D of Fig. 2.

30 Fig. 5 is an elevation of the flush valve applied to a water closet.

Fig. 6 is a detail of the relief valve dog.

Fig. 7 is a detail or bottom view of the relief valve.

35 Fig. 8 is a detail of the handle.

Fig. 9 is an end elevation of the handle. α designates the usual barrel of the flusher; b the cored intake passage; c the valve seat provided with a spider d to guide

40 the stem of the valve e . The valve e is a compound piston valve, the lower portion acting as the inlet valve, provided with the packing ring f and an annular flange g that fits over the outside of the valve seat.

45 This outside flange is advantageous as it avoids the unpleasant hissing sound which accompanies the operation of so many valves, especially where the rim fits to the inside of the valve seat. The main body of

50 the valve or the connection between the piston and the valve proper is in the form of a V h through one leg of which is a passage-way i from the intake passage b to the chamber behind the piston. This allows the 55 ingress of the water under pressure so that inasmuch as the area of the piston is greater

than the area of the valve proper, the valve always tends to close and remain closed.

The upper end of the V terminates in a neck or housing j internally threaded and 60 arranged to house part of the operating parts of a relief valve, of which k is the threaded cap that fits into the threaded end of the neck j and acts as an abutment for one end of the coil spring l , which tends to 65 keep the relief valve m upon its seat. This relief valve is detailed in Fig. 7, which is a bottom plan view showing that it has guiding wings three in number.

Between the legs of the V is pivoted the 70 dog n in a hole o . This dog is so balanced by gravity that it ordinarily bears against the bottom of the valve stem z , as shown in Fig. 1. However, if the outer end of the dog is pushed down, as shown in Fig. 3, it serves 75 to raise the relief valve. This immediately releases the pressure behind the piston-like valve, and the pressure on the lower end of the valve now serves to lift the large valve portion off of the seat, allowing the water to 80 run through the valve seat and over its walls down through the outlet pipe p into the water-closet bowl, which is thereby flushed.

The tail of the dog is thrust down to raise the relief valve by movement of the operating lever q , which may be up, down or to either side, or in any intermediate direction. Any movement of the handle pushes in the plunger r as indicated in Fig. 3, depressing the tail of the dog and raising the relief 90 valve. This movement is resisted by the coil spring s which serves both this function and the function of holding the washer and packing t properly seated.

The plunger stem and the plunger head 95 may be disassembled by unscrewing them (Fig. 1). It will be noted that the handle q is assembled with respect to the plunger by the nut u having a turned-in rim which forms a socket for the handle. A lock nut w 100 serves to keep this nut u in any desired position of adjustment.

Now referring to Fig. 8, the means for regulating the length of the flushing operation during actuation of the handle will be 105 seen. Now obviously the amount of inward projection of the plunger depends upon the projection of the set screw v in the end of the handle. The farther this is turned out the farther in the plunger goes. The farther in 110 the plunger is located toward the dog n , the farther the compound valve rises before the

dog drops off from the end of the plunger and allows the relief valve to close and the closing operation of the compound valve to follow.

- 5 From this description it appears that the adjustment of the flushing operation is very simple. All that is necessary is to release the lock nut and retaining nut u , thereby disassembling the handle from the rest of the relief valve operating parts. A screw-driver may then be called into service to turn the set screw v more or less into the end of the handle.

The handle is made in the form of two nuts so that one may be tightened against the other, x being a jam nut which may be tightened against the end of the valve when the set screw v has been adjusted to the proper position. This is effected by the use 20 of a screw-driver in the slot v (Fig. 9).

What I claim is:

1. In a flushing valve, the combination of a barrel, a compound valve reciprocating in said barrel provided at one end with a large 25 valve portion and at the other end with a casing housing a small valve and having a V-like body portion, a tripping device for the small valve located in the opening of the center of the V, and a passage-way from the 30 inside of the valve to the outside of the valve through one of the legs of the V.

2. In a flushing valve, the combination of a barrel, a compound valve provided with a dog and a relief valve operated by the dog, 35 a plunger reciprocable through the side of the barrel and adapted to contact and actuate said dog, a handle extending axially in line with the plunger adapted to project the plunger inward when said handle is oscillated, and means adjustable in the direction 40 of the axis of the handle for adjusting the

point of contact between said handle and plunger.

3. In a flush valve, the combination of a barrel, a compound valve reciprocating in 45 the barrel and provided with a relief valve and a dog for operating the relief valve, a plunger reciprocating through the side of the barrel for tripping the dog, a handle for projecting the plunger inward, and adjustable means on the end of the handle for regulating the amount of projection of the plunger, for the purpose specified.

4. In a flush valve, the combination of a barrel, a compound valve reciprocating in 55 the barrel and provided with a relief valve and a dog for opening the same, a plunger reciprocating through the side of the barrel and adapted to contact and actuate said dog, a handle for projecting the plunger inwardly, a spring for resisting the inward projection, and a set screw in the end of the handle for regulating the inward projection of the plunger, for the purpose specified.

5. In a flush valve, the combination of a 65 barrel, a compound valve reciprocating in the barrel and provided with a relief valve and a dog for opening the relief valve, a plunger reciprocating through the side of the barrel for tripping the dog, a spring for 70 normally keeping the plunger withdrawn, a handle against which the plunger projects, a set screw in the end of the handle, and a lock nut in conjunction with the end of the handle and the set screw for keeping the set 75 screw in various positions of adjustment which regulates the amount of the projection of the plunger, for the purpose specified.

In testimony whereof I sign this specification.

EDGAR J. BLOOM.
